UNITED STATES PATENT OFFICE.

WENZEL SCHOEDL, OF COMFREY, MINNESOTA.

SLED KNEE AND SPINDLE HUB.

Application filed January 29, 1921. Serial No. 441,040.

To all whom it may concern:

Be it known that I, WENZEL SCHOEDL, a citizen of the United States, residing at Comfrey, in the county of Brown and State 5 of Minnesota, have invented certain new and useful Improvements in Sled Knees and Spindle Hubs; and I do hereby declare the following to be a full, clear, and exact description of the invention, such as will enable 10 others skilled in the art to which it appertains to make and use the same.

This invention relates to a sled knee spindle hub and is designed to provide a device affording a ready attaching means for the 15 sled runner to the axles or spindles of the vehicles.

It is an object of this invention to provide the sled runner with means capable of ready and easy attachment to the vehicle, 20 which means is also capable of quick and easy assembling and disassembling.

This and other objects and advantages of the invention will be apparent from the following description made in connection with 25 the accompanying drawing, in which like reference characters refer to the same parts throughout the different views and, in which,

Fig. 1 is a view in side elevation of a runner with the hub shown thereon, a part 30 thereof being shown in section;

Fig. 2 is a partial top plan view of the device;

Fig. 3 is a central vertical section taken longitudinally of the spindle hub as the parts 35 are shown in Figs. 1 and 2.

Fig. 4 is a partial view similar to Fig. 1, showing a modification.

Referring to the drawings:

A sled runner 1 of ordinary construction is 40 shown having on its tread or bearing surface the usual metal reinforcement 2 and a block or post 3 is mounted upon this runner intermediate the ends thereof and is provided with lateral depending flanges 4 which embrace 45 the sides of the runner at the top portion thereof. This post is firmly secured to the runner by bolts 5 passing therethrough and a pair of dowel pins 6 are secured in the runner by having their heads disposed in recesses in the bottom thereof as shown in Fig. 50 1 and extend upwardly through holes in the top and bottom portions of post 3 and along the sides of the same intermediate these portions as illustrated. The heads of these 55 dowel pins rest upon the metal tread 2 and their ends project above the top of the post

3. These pins, as shown in Fig. 2, are located in the transverse central line of the post 3. The spindle hub 7 is provided with a base flange 8 of similar shape and size to the 60 top of post 3. This flange 8 is provided with holes suitably shaped to engage the ends of the dowel pins 6. The top of the post 3 and the flange 8 at the sides thereof are provided with bolt brackets 10 secured thereto by suitable screws and these brackets are adapted to receive nutted bolts 11 by which the flanges, and thus the hub member 7 and post 3 are firmly secured together, the correct relative position being maintained by the 70 dowel pins 6.

A brace member or yoke 12 is shown in Fig. 1 as passing across the top of flange 9 and provided with holes for the passage of the dowel pins 6. This brace member is suitably bent and bolted to the runner 1 at its ends. The hub member 7 is formed as a cap bearing and provided with the cap 13 which is provided with the flange and secured by the cap screws 14 to a similar flange on the 80 member 7. By providing the cap bearing, the hub can be used with spindles varying somewhat in size and shape.

In Fig. 4, the brace member 12' is shown as made in two separate parts, the ends of 85 which are bolted to extension flanges 15 provided on the flange 8' of the hub. A shim or filling piece 16 is placed across the top of post 3 and provided with holes for the passage of the dowel pins 6 to fill the space occupied by the brace 12.

Some brace members which will pass across the flange 9 of the post 3 are often provided with a pressed bead at the center thereof and the hub member 7 is provided 95 with a transverse slot 17 to fit over such bead when the brace having such a bead thereon is used.

The operation of the device, it is thought, will be readily understood from the above 100 description. The hub 7 is placed on the wheel spindle, which passes through the bore therein and the cap member 13 is suitably tightened to provide the necessary fit to the spindle. It will, of course, be understood 105 that the aperture in hub 7 may be provided with a suitable bushing or lining of anti-friction metal. With the parts assembled in Fig. 1 when the spindles are secured in the hub member 7, the runners are then in operative relation to the vehicle. If desired, one set of hub members 7 can be used and several 110

sets of runners each provided with the remainder of the structure can be interchangeably used therewith. The device is simple in construction, efficient in use and has a high 5 degree of flexibility and utility.

It will, of course, be understood that various changes may be made in the form, details and proportions of a device without departing from the scope of the applicant's invention, which generally stated consists in 10 the matter shown and described when set forth in the appended claim.

What is claimed is:

A sled knee structure having in combination 15 a runner and post secured thereto and upstanding therefrom intermediate its ends, said post being provided with flanges at its

base portion embracing the top of said runner and provided with a flange at its upper portion, spaced dowel pins secured in said 20 runner and passing upwardly through said post in the transverse center line thereof, a spindle hub having a base flange similar to the flange at the upper portion of the post adapted to be disposed thereover and having 25 openings therein arranged to engage said dowel pins and means for bolting said last mentioned flanges together.

In testimony whereof I affix my signature in presence of two witnesses.

WENZEL SCHOEDL.
